Primary Examiner — Kevin K. Rudzinski(74) Attorney, Agent, or Firm — Buchalter, Kari L. Barnes(57) CLAIM

We claim the ornamental design for a sun garment, as shown and described.

DESCRIPTION

FIG. 1 is a first side view of a sun garment showing the design in a position of use as viewed from a front side of a person; and,

FIG. 2 is a second side view of the sun garment illustrated in FIG. 1 in a position of use as viewed from a back side of a person.

The broken lines are included for the purpose of illustrating environmental subject matter and form no part of the claimed design.
